EDWARD E. RUSHTON, OF WILKINSBURG, PENNSYLVANIA.

FUEL-OIL BURNER.

1,180,607.

Specification of Letters Patent. Patented Apr. 25, 1916.

Application filed October 30, 1913. Serial No. 798,310.

To all whom it may concern:

Be it known that I, EDWARD E. RUSHTON, a citizen of the United States of America, residing at Wilkinsburg, in the county of Allegheny and State of Pennsylvania, have invented certain new and useful Improvements in Fuel-Oil Burners, of which the following is a specification, reference being had therein to the accompanying drawing.

0 This invention relates to a fuel oil burner and has for its object the provision of means for controlling and regulating the feeding of oil and a fluid such as air or steam, as a fuel to the nozzle of the burner, the control 5 being effected by operating a valve stem which is common to the oil supply and fluid supply valves, under such conditions setting up what may be termed a unit control for the two constituents of the fuel.

0 A further object of the invention is to provide an oil burner including an oil supply and a fluid supply valve, each of which is operated from a common means and constructed in such a manner with respect to 5 each other than when the oil supply valve is shifted to admit oil for passage to the burner, the fluid supply valve will be simultaneously operated, so as to admit the necessary amount of fluid for obtaining a thoroughly satisfactory combustible mixture of 0 fuel, or in other words the valves are so graded with respect to each other, that when the oil supply valve is open the proportional amount of fluid necessary is simultaneously 5 supplied with the supplying of the oil.

Further objects of the invention are to provide an oil burner including means for thoroughly atomizing oil before the same is discharged through the nozzle of the burner.

0 A further object of the invention is to provide an oil burner with means, in a manner as hereinafter set forth to prevent, when the burner is in use, the complete withdrawal of the valve stem thereby overcoming 5 any possibility of the operator being burned when the device is in use.

A further object of the invention is to provide an oil burner, in a manner as hereinafter set forth, whereby the elements 0 thereof are so constructed to enable the burner to be set up in any size, large or small thereby permitting of the burner being employed for any purposes where it is found applicable.

5 A further object of the invention is to provide, in a manner as hereinafter set

forth, an oil burner whereby the number of parts are reduced to a minimum, under such conditions obtaining an unusually convenient adjustment when occasion so requires and to furthermore set up a burner whereby the elements thereof are independent of each other from a constructive standpoint to enable if any part becomes damaged to only discard the damaged part without necessitating the entire discarding of the burner, this constructive arrangement enabling a new part to be substituted for a damaged part, and under such conditions it is obvious that considerable saving in expense is obtained.

Further objects of the invention are to provide an oil burner which is unusually simple in its construction and arrangement, formed of few parts, strong, durable, thoroughly efficient in its use, conveniently adjusted and comparatively inexpensive to manufacture.

With the foregoing and other objects in view, the invention consists of the novel construction, combination and arrangement of parts as hereinafter described and illustrated in the accompanying drawings wherein is shown an embodiment of the invention, but it is to be understood that any change, variations and modifications can be resorted to which fall within the scope of the claims hereunto appended.

In the drawings wherein like reference characters denote corresponding parts throughout the several views, Figure 1 is a longitudinal sectional view of an oil burner in accordance with this invention, Fig. 2 is a section on line X—X of Fig. 1, Fig. 3 is a view of the hand wheel for adjusting the valve stem, and Fig. 4 is a section on line Y—Y Fig. 1.

Referring to the drawings in detail, 5 denotes a cylindrical housing having one end thereof contracted as at 6, with the inner face of the latter for a portion of its length threaded as at 7, smooth as at 8, and threaded as at 9, the smooth portion 8 being interposed between the threaded portions 7, 9. The inner diameter of the contracted end 6 at the smooth portion 8, of its inner face, is greater than the inner diameter of said contracted end at that portion of its inner face which is provided with the threads 9, thereby forming a shoulder or 105 seat 10, and each end of the housing 5 is open.

- Mounted against the shoulder 10, is an apertured disk 11, having that face thereof out of contact with said shoulder 10, countersunk as at 12 to form a concaved recess.
- 5 Mounted in the contracted end 6 of the housing 5, is a packing gland 13, formed with a concaved recess 13^a. The packing gland 13 is peripherally threaded and engages with the threads 7. Interposed between the disk 11 and the gland 13, and mounted in the recesses 12, 13^a is a packing 14 for an adjustable valve stem 15, the latter extending through the contracted end 6 into the larger portion of the housing 5, as well as projecting through the disk 11 and gland 13. The stem 15 projects outwardly with respect to the reduced end 6 of the housing 5 and has its outer end squared as at 15^a and further formed with a cylindrical threaded extension 15^b. Mounted upon the squared portion 15^a of the stem 15 is a hand wheel 16 substantially in the form of what may be termed a four pointed star. Positioned upon the extension 15^b is a nut 15^c, which engages with the wheel 16 for maintaining it upon the stem 15. The squared portion 15^a of the stem 15 prevents the wheel 16 from turning independently of the stem.
- 10 The outer face of the wheel 16 is provided with indications 16^a, 16^b and 16^c and 16^d. These indications are located at the respective points of the wheel and mark various positions of the valves from closed to full opening.
- 15 The cylindrical housing, in proximity to its reduced end, has arranged therein an integral partition 17, forming a fluid chamber 20, and said partition 17 centrally thereof is provided with an opening 18, for establishing communication between the compartment 17^a, formed forwardly of the partition 17 and the fluid chamber 20.
- 20 The opening 18 is closed through the medium of a fluid supply valve 19, the latter being conical in contour and formed integral with the forward end of the stem 15. The base of the valve 19 is of less diameter than the diameter of the forward end of the stem 15, whereby a flange or shoulder 19^a is provided which when the valve stem 15 is shifted to the limit of its forward movement, abuts against the partition 17 whereby the opening 18 is closed.
- 25 The housing 5 is provided with an inclined passage 21, which establishes communication between the fluid chamber 20 and a fluid inlet nipple 22. The nipple 22 is peripherally threaded and engaging with the threads of the nipple 22 is a flanged collar 23, for coupling to the nipple a fluid supply pipe 24. The housing 5 diametrically opposite the nipple 22 is provided with an oil inlet nipple 25, which is peripherally threaded, and engaging with the threads of the nipple 25, is a flanged collar 26 for coupling an oil supply pipe 27. By coupling the pipes 24, 27 to the nipples 22, 25, in the manner as stated, the housing 5, can be adjusted to various inclinations or to a vertical or horizontal position.
- 30 Mounted in the housing 5, at the larger end thereof, is the reduced portion 27^a of a stem guide and seat member. The larger portion of said member is indicated at 28 and provides a shoulder 29 which abuts against the housing 5. The reduced portion 27^a of said member extends to a point in close proximity to the partition 17 and the said reduced portion 27^a is peripherally threaded for engagement with the threads 30 of the inner face of the housing 5, whereby said member is detachably connected to the said housing 5. The reduced portion 27^a at its inner end is provided with an annular pocket 31, which opens into a longitudinally extending passage 32, the latter communicating with an inclined port 33, which opens into a fluid chamber 34, formed in the enlarged portion 28 of the stem guide and seat member. The reduced portion 27^a of the stem guide and seat member is formed centrally with an oil receiving chamber 35, which communicates with an inclined passage 36 formed in said reduced portion 27^a. The housing 5 is formed with an inclined port 37, the latter opening at one end into the oil inlet nipple 25, and at its other end registering with the passage 36. Arranged centrally of the reduced portion 27^a of the stem guide and seat member, and extending from the chamber 35 to the inner terminus of said reduced portion 27^a is a longitudinal bore 38, in which is mounted an auxiliary valve stem 39, which is formed integral with the forward end of the valve 19, and normally projects into and is of less diameter than said oil receiving chamber 35. The auxiliary stem 39 terminates in a conical needle valve 40, which engages a valve seat 44, the latter being formed by providing the forward terminus of the reduced portion 27^a of the stem guide and seat member with a tapering bore, the latter communicating with the chamber 35, and the base of the valve 40 is of less diameter than the forward terminus of the stem 39.
- 35 The enlarged portion 28 of the combined stem guide and seat member is provided with an annular recess to form the fluid chamber 34, and by forming the annular recess, a centrally disposed tubular member 41 is left, having a longitudinally extending and centrally disposed bore 42 which forms a continuation of the valve seat 44 and into which is adapted to extend the forward end of the valve 40. The member 41, at its forward end is peripherally grooved, as at 43, for a purpose to be presently re-

ferred to. The inner face of the enlarged portion 28 of the stem guide and seat member is provided with threads 45.

Extending into the enlarged portion 28 of the stem guide and seat member is a cylindrical member 46, having its inner face tapering for a portion of its length as at 47, forming one wall of the chamber 34. A portion of the inner face of the member 46, in longitudinal section, is rounded as at 48, the tapering portion 47 merging in the rounded portion 48, which latter opposes the groove 43, and provides in connection with said groove 43, an annular outlet 49 for the fluid chamber 34, the outlet 49 being curved in longitudinal section. The bore of the member 46, that is that portion projecting forwardly from the rounded portion 48, as indicated at 50 is smooth and of the same diameter throughout and at its outer end formed with threads 51, and secured in the member 46, intermediate the ends of the portion 50 of the inner face of said member 46, is a partition 52 formed with a series of ports 53^a, which incline toward the center of the outer face of the partition 52. The partition 52, in connection with the members 41, 46, provides a mixing chamber 53 for the oil and fluid, the oil being supplied into the chamber 53 by the bore or passage 42, the fluid being supplied by the passage 49.

The member 46, intermediate its ends, is provided with a peripheral collar 54, which abuts against the forward end of the stem guide and seat member, and said member 46 is further provided with peripheral threads which engage with the threads 45, whereby the member 46 is detachably connected to the stem guide and seat member.

The member 46 is furthermore provided with peripheral threads 55 for connecting the forward end of the burner to a support, if it be desired.

Extending in the forward end of the member 46 and spaced from the partition 52, as well as engaging with the threads 51, is a coupling member 56 formed with a tapering recess 57 and a socket 58, which communicates with the recess 57. The wall of the socket 58 is threaded and engaging with said threads is the inner peripherally threaded end of a nozzle 59, the inner end of the latter being beveled as at 60, forming a continuation of the wall of the recess 57. The nozzle 59 is provided with a passage 61, which communicates with a tapering outlet 62, at the forward end of the nozzle 59. The member 56 is utilized for coupling the nozzle 59 to the member 46.

The valve stem 15, adjacent the valve 19 is enlarged as at 63, and threaded for engagement with the threads 9 of the reduced end 6 of the housing 5. When the burner is set up, the enlarged portion 63 of the valve

stem 15 prevents the entire withdrawal of said stem due to the fact that said enlarged portion 63 on the rearward movement of the valve stem will abut against the disk 10, under such conditions arresting further rearward movement of the stem 15. By this arrangement liability of burning of the operator is prevented.

The fluid, such as air or steam as the case may be, is supplied to the fluid chamber 34, through the medium of the inclined port 33, the latter giving a whirling action to the fluid and as the fluid is discharged by the port or passage 49 into the mixing chamber 53, it thoroughly mixes with the oil, at the same time atomizing the oil and the atomized mixture is discharged through the inclined ports 53^a and directed into the nozzle 59, by the walls of the tapering recess 57.

By forming the oil supply valve 40, integral with the valve stem, which carries the fluid supply valve 19, the said valves are simultaneously operated and are under what may be termed a unit control. The valves 19 and 40 are so proportioned that the same relative proportions of fluid and oil are fed at different openings.

The bore 38, constitutes a guide for the auxiliary stem 39, while the disk 8 and gland 13 constitute a guide for the valve stem 15.

Although the element 39 is termed an auxiliary stem, yet it is to be understood that it is nothing more than an integral extension of the valve stem 15.

The peripherally threaded enlarged portion 63, of the valve stem 15, in connection with the threads 9, provides means for maintaining the valve stem in the position to which it has been adjusted.

What I claim is:—

1. An oil burner comprising a burner body provided with a mixing chamber and further provided with means for conducting oil to said chamber and for further supplying air in a whirling manner to said chamber, and a pair of valvular elements operating in unison and controlling the supply of oil and air to said chamber.

2. An oil burner comprising a mixing chamber, an oil conducting means communicating at one end with said chamber and having its other end provided with a valve seat, an air conducting means communicating with said chamber and having one end provided with an opening, a valve for controlling the supply of oil adapted to engage said seat, a valve for controlling the supply of air for closing said opening, each of said valves being conical in contour, and means for operating said valves in unison.

3. An oil burner comprising a mixing chamber, an oil conducting means communicating at one end with said chamber and having its other end provided with a valve

- seat, an air conducting means communicating with said chamber and having one end provided with an opening, a valve for controlling the supply of oil adapted to engage said seat, a valve for controlling the supply of air for closing said opening, each of said valves being conical in contour, and an adjustable valve stem integral with said valves for operating them in unison.

4. An oil burner comprising a mixing chamber, an oil conducting means communicating at one end with said chamber and having its other end provided with a valve seat, an air conducting means communicating with said chamber and having one end provided with an opening, a valve for controlling the supply of oil adapted to engage said seat, a valve for controlling the supply of air for closing said opening, each of said valves being conical in contour, an adjustable valve stem integral with said valves for operating them in unison, and means to prevent the complete withdrawal of said valve stem when the burner is under working conditions.

5. An oil burner comprising a mixing chamber, means for conducting oil to said chamber, means for conducting air to said chamber, a conical valve for controlling the supply of oil to said chamber, a conical valve for controlling the supply of air to said chamber, said conducting means for the air discharging eccentrically into said mixing chamber, whereby a whirling action of the air is set up when supplied to the mixing chamber thereby causing a thorough atomizing of the oil, a nozzle communicating with said chamber, and means for operating said valves in unison.

6. An oil burner comprising a mixing chamber, means for conducting oil to said chamber, means for conducting air to said chamber, a conical valve for controlling the supply of oil to said chamber, a conical valve for controlling the supply of air to said chamber, said conducting means for the air discharging eccentrically into said mixing chamber, whereby a whirling action of the air is set up when supplied to the mixing chamber thereby causing a thorough atomizing of the oil, a nozzle communicating with said chamber, and an adjustable valve stem integral with said valves for operating them in unison.

7. An oil burner comprising a mixing chamber, means for conducting oil to said chamber, means for conducting air to said chamber, a conical valve for controlling the supply of oil to said chamber, a conical valve for controlling the supply of air to said chamber, and means to prevent the complete withdrawal of the valve stem when the burner is under working conditions.

8. An oil burner comprising a mixing chamber, means for conducting oil to said chamber, means for conducting air to said chamber, a conical valve for controlling the supply of oil to said chamber, a conical valve for controlling the supply of air to said chamber, said conducting means for the air discharging eccentrically into said mixing chamber, whereby a whirling action of the air is set up when supplied to the mixing chamber thereby causing a thorough atomizing of the oil, a nozzle communicating with said chamber, an adjustable valve stem integral with said valves for operating them in unison, and means to prevent the complete withdrawal of the valve stem when the burner is under working conditions.

9. An oil burner comprising a burner body provided with a mixing chamber, a fuel diffusing member in said mixing chamber, said body being provided with means for conducting oil to said chamber and for further supplying air in a whirling manner to said chamber, and a pair of valvular elements operating in unison and controlling the supply of oil and air to said chamber.

10. An oil burner comprising a burner body provided with a mixing chamber, a screen plate having inclined passages therein inwardly directed toward their outer ends arranged in said mixing chamber, said body being provided with means for conducting oil to said chamber and for further supplying air in a whirling manner to said chamber, and a pair of valvular elements operating in unison and controlling the supply of oil and air to said chamber.

In testimony whereof I affix my signature in the presence of two witnesses.

EDWARD E. RUSHTON.
